UNITED STATES PATENT OFFICE

2,057,920

STITCHING MACHINE

William Rose, Islip, N. Y.

Application October 12, 1931, Serial No. 568,399
Renewed January 3, 1934

26 Claims. (Cl. 112—80)

This invention relates to stitching machines such as are used for making rugs, tapestries and the like in which the stitches are applied to a canvas or burlap backing according to the design desired. In making rugs, tapestries and the like by applying loop stitches to a canvas or burlap backing a loop was ordinarily inserted within the meshes of the burlap and the loop inserting instrument was then withdrawn. However, it was usually desirable to cut the loop to give a cut pile effect, but this cutting operation usually had to be carried out by hand after the loop stitches had been applied in a desired design or pattern. In addition, it was not possible to use a variety of materials for making the stitches such as pieces of fabric or rags, due to the limitations of the apparatus employed, and due to the difficulties of holding the loops in position after they had been formed and while they were being cut.

An object of the present invention is to provide a mechanism adapted for either hand utilization or machine utilization, which may be used for making rugs, tapestries and the like, which machine will be of inexpensive construction and will not be readily deranged, even though subjected to considerable handling and usage, which will accurately hold the loops in position in the burlap both when the loop is being formed and when the loop forming mechanism is being withdrawn from the loop.

Another object is to provide a stitching machine of the character above-described which will make loop stitches and will cut such loop stitches by a single operation, said machine being of relatively simple construction and of relatively low cost.

Another object is to provide an inexpensive and simple apparatus for making rugs, tapestries and the like particularly which is to apply a design or pattern to canvas or burlap backing by means of loop stitches, which mechanism will be adapted to handle a wide variety of stitching materials, such as rags, strips of cloth, yarn and so forth.

Other objects will be obvious and will appear during the course of the following specification.

In accomplishing the above objects a stitching machine construction has been provided with a plurality of longitudinally reciprocating members, one of which provides an opening between the warp and weft threads of the canvas or burlap backing; a second of which inserts a loop in said backing, and the third of which

cuts the loop, these members being preferably successively operated in the order described.

In a manually actuated stitching mechanism it is most convenient to employ one manual grip device to insert the opening member in the backing material while another manual actuator may be provided for successively operating the stitching and cutting members.

In the preferred embodiment preferably in association with these longitudinally operating members are a plurality of stitch holding members, one of which is adapted to retain the half-formed stitch previously made, while the new stitch is being formed, and the other of which is adapted to hold the stitching material being fed after it has been inserted in the fabric to form a loop. These holding members or means are preferably so arranged that they will release the thread or stitching material during the stitching action so that it may be readily fed through the backing, while at the same time they will hold the loop firmly against distension during the cutting operation and also prevent the half formed stitch from being drawn out when the next loop is being formed by the pulling effect of the looping member.

The above and other objects will appear more clearly from the following detailed description, when taken in connection with the accompanying drawings, which illustrate one embodiment of the inventive idea.

In the drawings:

Fig. 1 is a side elevation of the machine in position before the members are moved;

Fig. 2 is a plan view of the machine from the top corresponding to Fig. 1;

Fig. 3 is a detail in section of a spring support for the needle;

Fig. 4 is a plan view from the bottom corresponding to Fig. 1;

Fig. 5 is a longitudinal section on line 5—5 of Fig. 4;

Fig. 6 is a detail showing a ratchet mechanism mounted on the slide;

Fig. 7 is a section on line 7—7, Fig. 5;

Fig. 8 is a section on line 8—8, Fig. 5;

Fig. 9 is a longitudinal section of the mechanism at the start of the stitching operation;

Fig. 10 is a longitudinal section of the mechanism at the completion of the stitching action;

Fig. 11 is a longitudinal section of the mechanism after the cutting action is completed; and the next stitch is about to be made;

Fig. 12 is a detail showing the ratchet action in the released position;

Fig. 13 is another detail showing the ratchet in the disengaged position;

Fig. 14 is an enlarged detail showing one form of point for the cutting member; and

Fig. 15 shows one form of point for the stitching needle.

The machine as illustrated in the drawings above described comprises a frame with a suitable handle at one end and terminating in the pointed guide at the opposite end. The point of this guide is inserted in the fabric and the members are operated back and forth within the guide by the action of the slide or driving mechanism. The yarn is suitably fed through the guide so as to be engaged by the forward movement of the stitching needle which thus inserts the yarn through the fabric leaving a loop when the needle is withdrawn.

In this invention a second member is brought into operation after the loop has been formed and by the continued motion of the mechanism this member cuts the loop so that the machine performs a complete stitching and cutting action in each operation. In this operation an escapement provided in the mechanism releases the stitching needle from the driving action of the machine while the cutting member is moved forward into action.

A clamp is provided to hold the last stitch in place when the machine is in operation and a second clamp is provided which is brought into action to clamp the feeding end of the yarn during the time the cutting member is in action so that both ends of the loop are held in tension when the loop is being cut. The second clamp is operated by a ratchet mechanism so that the yarn is released as soon as the cutting action is completed thereby avoiding any tendency to withdraw the feeding end of the yarn from the fabric as the mechanism is changed for the next step.

In the manufacture of rugs by the loop stitch as referred to a great deal of time is consumed in cutting the loops after the stitching is completed, with the present machine this labor is avoided.

In the drawings, 11 is the frame of the machine which is constructed in the form of a rectangular bar upon which the slide operates. This frame is connected with the handle 12 and has the hollow guide 13 mounted on the lower end. The slide 14 is preferably made from a piece of bent stock as indicated, with one leg 15 extended to form a handle. The slide moves freely on the frame 11 and has mounted thereon a presser foot 16 formed of wire and arranged to engage the fabric b when the stitch is being made. The yarn a is fed through suitable eyes and into an opening 18 in the needle guide 13 and a clamp 17 is provided to clamp the yarn against 13a when the cutting member is in action. The needle guide 13 is provided with a foot 19, preferably faced with soft rubber which engages the last stitch c and holds the yarn forming this stitch in place while the machine is in operation.

The guide 13 is provided with a hollow point 20 which is inserted in the fabric b and forms an aperture in the fabric for the yarn and for the needle and cutting member. The stitching member is indicated by 21 and the lower member 22 is the cutting member, these members being operated by the slide 14. Member 22 is rigidly secured to the slide by the offset portion 38 and the upturned end 39 which enters an aperture in the slide and is held in place by

spring 40. The stitching needle 21 is operated by the slide 14 during the preliminary movement of the slide and is then released from the slide. This needle, as indicated in Figs. 1, 9, 10 and 11, is bent at right angles at 31, passes through a slot 33 in the frame 11 and terminates in the T head 32. In the position shown in Fig. 5, the bent portion 31 is engaged by the edge of the curved channel 34 formed in the slide 14 thereby causing the needle to move with the slide until the T head engages the incline 35 on the frame 11. This deflects the needle against the action of the flat spring 37 and disengages the shoulder of 31 from 34 so that the needle passes into the channel 34 thus arresting its motion by this escapement as the movement of the slide is continued.

It will be observed that in the mechanism thus far described, the needle 21 and member 22 move together as indicated in Fig. 9 until the loop is formed and the cutting member 22 being shorter than 21 does not injure the strands of the yarn. The continued movement of the slide, after the loop is formed, moves the cutting member only as indicated in Fig. 10 where the member 22 is projected beyond the needle 21 and has cut the yarn a at d.

The needle 21 is preferably formed with a blunt curved edge as indicated at 21a in Fig. 15 so as to form a channel for the yarn a below the curved channel of guide 13 as indicated in the longitudinal sectional drawings. The member 22 is preferably flat shaped to slide on the needle 21 and has a forked cutting edges as indicated at 22a in Fig. 14. These members are held against the guide 13 by the shoe 42 which is held in position by spring 46. This shoe has a pair of lugs 43, Fig. 3, and a pin 44 inserted in slots 45 in an expanded portion 13b of the guide 13 engages these lugs and the spring 46 thereby providing tension to hold the needle 21 and member 22 in place. The shoe 42 is also provided with a base for the rubber pad 19 which rests upon the stitches.

The guide 13 and the spring 53 are clamped by plate 52 and screw 51 to the frame 11. The spring 53 is bent upon itself having an upper section 54 which supports the U-shaped clamp 17, which, when in the depressed position clamps the yarn a against 13a as indicated in Fig. 10. An aperture is provided at 55 in the slide to clear the incline 35 and the spring 54. During the stitching movement of the slide which has just been completed in Fig. 9, the spring 54 is not depressed and the yarn is free to be fed to the loop.

When the slide has advanced to the cutting position as indicated in Fig. 10 the spring 54 is depressed to bring the clamp 17 into action. This is secured by the ratchet dogs, Figs. 6, 12 and 13, which are mounted on the end 15 through the pivot 58 and comprise the dogs 56 and 57 held in tension by spring 59 and restricted by the stop 60. A shoulder is formed on each dog at 61 which engages the spring 54 and depresses the spring as these dogs move forward on the incline. The spring 54 is notched as indicated at 62—62, Fig. 2, so that when the dogs 56 and 57 reach these notches, the spring is released and the clamp 17 is thereby released. This release is arranged to take place after the loop has been cut. Upon the return of the slide 14 the inclined shoulder 63 of spring 54 forces the dogs 56 and 57 apart as indicated in Fig. 13 so that on the

return movement of the slide the clamp 17 is not brought into action.

In the operation of the machine, the yarn *a* is threaded through the clamp 17 and the aperture 18 and around the end of the needles. The point 20 is then inserted in the fabric and the slide moved down which first forms the loop stitch as indicated in Fig. 9, then clamps the feeding end of the yarn at 17, stops the movement of the stitching needle and moves forward the cutting member until the loop is cut, then the clamp 17 is released, the presser foot 16 is held against the fabric and the frame is withdrawn until the point 20 is clear of the fabric when the machine is tilted as indicated in Fig. 11 to bring the point 20 into position for another stitch. The point 20 is then inserted in the fabric and the slide is raised to withdraw the members, and as the slide is moved down again the members are brought into alignment with the point 20 and thus a new stitch is made. The width of the stitch is determined by the extent of the deflection of point 20 in the position shown in Fig. 11. This in turn is determined by the free movement of the members permitted by the shoe 42, hence if it is desired to vary the size of the stitches all that is necessary is to change shoe 42 to permit the necessary movement between the lugs 43 and the frame 11, Fig. 3.

This invention can be applied in a variety of forms by those skilled in the art to which it pertains and includes a full range of equivalents and alternatives.

It is apparent that the functions of the opening member 13, the stitching member 21 and the cutting member 22 might be combined in less than three longitudinal reciprocating members if desired, and it is also apparent that one or more of the members 13, 21 and 22 might be omitted. Other means of protecting the backing *b* from being cut than the tubular means 13 shown may be provided and if desired the forked cutter 22 might be arranged to be inserted in the backing *b*, without danger of cutting the warp and weft threads thereof. The members 21 and 22 might be combined so that the stitching member 21 would have the action of the cutting member 22 upon the loop when it has formed.

In place of the holding means 19 for the half-formed loop and the holding means 13a—17 for the stitching material *a*, other holding means may be provided to replace the holders 13a, 17 and 19 as shown. The holder 19 may be modified so as to grip the half-formed loop *C* positively in respect to the backing *b* if desired. As is apparent from Figs. 7, 8 and 15, the needle 21 may be readily shaped to receive strips of materials, whether straight, folded or twisted, as well as the round yarn as shown.

Having thus described my invention, I claim:

1. In a stitching machine, the combination of a frame with a hollow point engaging the fabric to be stitched, a slide moving relative to said frame and a pair of members operated by said slide and moving in said hollow point, one of said members applying stitches to the fabric and the other member cutting the stitch and means for moving the cutting member to a greater extent than the stitching member by said slide.
2. In a stitching machine, the combination of a frame with a hollow point engaging the fabric to be stitched, a slide moving relative to said frame and a pair of members operated by said slide and moving in said hollow point, one of said members applying stitches to the fabric and the

other member cutting the stitch by a continued movement of the slide after the stitch is formed.

3. In a stitching machine, the combination of a frame with a hollow point engaging the fabric to be stitched, a slide moving relative to said frame and a pair of members operated by said slide and moving in said hollow point, one of said members having a stitching action and the other member having a cutting action on the stitch.

4. In a stitching machine, the combination of a frame with a hollow point engaging the fabric to be stitched, a slide moving relative to said frame and a pair of members operated by said slide and moving in said hollow point, said members being moved together during part of the operation of said machine and one of said members moving independently of the other during another part of the operation of said machine and cutting the stitch after it is formed.

5. In a stitching machine, the combination of a frame with a hollow point engaging the fabric to be stitched, a slide moving relative to said frame and a pair of members operated by said slide and moving in said hollow point and an escapement for stopping the motion of one of said members when the stitch is formed while the other member moves with the slide to cut the stitch.

6. In a stitching machine, the combination of a frame with a hollow point engaging the fabric to be stitched, a slide moving relative to said frame and a pair of members operated by said slide and moving in said hollow point, one of said members forming a stitch and a cam on said frame controlling said member to release it from movement with said slide and the other member cutting the stitch formed by the first member.

7. In a stitching machine, the combination of a frame with a hollow point engaging the fabric to be stitched, a slide moving relative to said frame, a needle for making a loop stitch operated by said slide and a member operated by said slide in said hollow point for cutting the loop of said member.

8. In a stitching machine, the combination of a frame with a hollow point engaging the fabric to be stitched, a slide moving relative to said frame, a needle for making a loop stitch operated by said slide and a second member having a cutting edge at the end operated by said slide in said hollow point for cutting the loop of said stitch by a forward movement of said second member.

9. In a stitching machine, the combination of a frame with a hollow point engaging the fabric to be stitched, a slide moving relative to said frame, a needle for making a loop stitch operated by said slide, means operated by said slide in said hollow point for cutting the loop of said stitch, and means for securing said stitch during the cutting operation against the action of the cutting means.

10. In a stitching machine, the combination of a frame with a needle guide engaging the fabric to be stitched, a slide moving relative to said frame, a needle for making a loop stitch operated by said slide, a second member for cutting said loop and means for holding both ends of the stitch during the cutting operation.

11. In a stitching machine, the combination of a frame with a needle guide engaging the fabric to be stitched, a slide moving relative to said frame, a needle for making loop stitches operated by said slide, means associated with said

- slide for cutting each loop stitch and means operated by said slide for securing the stitch during the cutting operation against the pull of the cutting means.
5. 12. In a stitching machine, the combination of a frame with a needle guide engaging the fabric to be stitched, a slide moving relative to said frame, a needle for making loop stitches operated by said slide, means for cutting each loop stitch 10 and means operative during the cutting operation for securing the stitch in the fabric against being pulled out by the cutting action.
13. In a stitching machine, the combination of a frame with a needle guide engaging the fabric 15 to be stitched, a slide moving relative to said frame, a needle for making loop stitches and a member for cutting each loop operatively connected with said slide and moving in said guide and a spring controlled shoe holding said needle 20 and member in alignment with said guide and engaging the stitch.
14. In a stitching machine, the combination of a frame with a needle guide engaging the fabric to be stitched, a slide moving relative to said 25 frame, a needle operated by said slide and moving in said guide and a spring controlled shoe engaging the stitch for normally holding said needle in alignment with said guide and limiting the deflection of said needle relative to said 30 guide whereby the length of the stitch is regulated.
15. In a stitching machine, the combination of a frame with a needle guide and yarn guide 35 engaging the fabric to be stitched, a slide moving relative to said frame, means for forming a loop stitch and means for cutting said stitch after it is formed operated by said slide and clamping means for clamping said yarn on both sides of the point where it is cut during the cutting part of said operation.
16. In a stitching machine, the combination of a frame with a slide thereon, a needle operated by said slide for forming a stitch, means including an inclined plane on said frame inclined in the 45 direction of movement of said slide for disengaging said needle from said slide after the stitch is formed and a member secured to and operating with said slide and having a cutting edge arranged to cut said stitch after the stitch is formed, 50 by the movement of said slide.
17. In a stitching machine, the combination of a frame with a slide thereon, a needle for forming a stitch operatively engaged by said slide, a channel in said slide, means for deflecting said 55 needle into said channel to disengage it from said slide at a predetermined position in the movement of said slide and a member secured to and operating with said slide arranged to cut said stitch after it is formed.
60. 18. In a stitching machine, the combination of a frame with a slide thereon, a yarn guide for the feeding end of the yarn, a needle operated by said slide for forming a stitch from said yarn, means for releasing said needle from movement 65 with the slide after the stitch is formed and means operated by said slide for clamping the feeding end of the yarn after the stitch is formed.
19. In a stitching machine, the combination of 70 a frame with a slide thereon, a needle operated by said slide for forming a stitch from a thread of yarn, means for releasing said needle from movement with said slide after the stitch is formed and means operated by the movement of the 75 slide in one direction only for clamping the yarn.
20. In a stitching machine, the combination of a frame with a slide thereon, a needle operated by said slide for forming a stitch from a thread of yarn, means for releasing said needle from movement with said slide after the stitch is formed, a member moving with said slide arranged to cut the stitch after it is formed and means operated by said slide for clamping the feeding end of the yarn during the cutting operation only.
21. In a stitching machine for inserting loop stitches in a backing fabric and for cutting such loop stitches, a frame provided with a member for engaging the fabric to be stitched and for providing an opening therein, a stitching member inserting a loop of the stitching material through said opening and a cutting member actuated subsequently to said stitching member for cutting said loop, said cutting member severing the loop by movement of the cutting means 10 longitudinally of the loop.
22. In a stitching machine for inserting loop stitches in a backing fabric and for cutting such loop stitches, a frame provided with a member for engaging the fabric to be stitched and for providing an opening therein, a stitching member 15 inserting a loop of the stitching material through said opening and a cutting member actuated subsequently to said stitching member for cutting said loop, said cutting member and said stitching member being relatively laterally extended and being further provided at their operative ends inserted through the openings in the backing with notches, the notch of the stitching member being relatively dull to carry the stitch and the notch in the cutting member being relatively sharp to sever the loop formed by the stitching member.
23. In a stitching machine for inserting loop 25 stitches in a backing fabric and for cutting said loop stitches after formation, means for successively providing an opening in the backing fabric, for inserting a loop in said opening and for cutting said loop after it has been formed, said cutting means including a forked cutter consisting of 30 a laterally extending member adapted to be inserted in said opening and means for advancing said forked cutter after said loop has been formed longitudinally of the loop to cut said loop.
24. In a stitching machine for inserting loop 35 stitches in a backing fabric and for cutting such loop stitches, a frame provided with a member for engaging the fabric to be stitched and for providing an opening therein, a stitching member inserting a loop of the stitching material through said opening and a cutting member actuated subsequently to said stitching member 40 for cutting said loop, said cutting member and said stitching member being relatively laterally extended and being further provided at their operative ends inserted through the openings in the backing with notches, the notch of the stitching member being relatively dull to carry the stitch and the notch in the cutting member being relatively sharp to sever the loop formed by the stitching member, and a shoe controlled by a spring for clamping the stitching material to the 45 backing during the process of making and cutting said loop stitch.
25. In a stitching machine for inserting loop 50 stitches in a backing fabric and for cutting said loop stitches after formation, means for successively providing an opening in the backing fabric, for inserting a loop in said opening and for cutting said loop after it has been formed, said cut- 55
